RAZOR BLADE SHARPENER

Edward P. Smith, Brooklyn, N. Y.

Application September 30, 1931
Serial No. 565,967

9 Claims. (Cl. 51—64)

My invention relates to razor blade sharpeners and refers particularly to devices adapted for sharpening blades of safety razors.

One object of my invention is a device adapted for sharpening both edges of a safety razor blade at the same time, thus obviating the necessity of removing and reversing the blade during the sharpening operation.

Another object of my invention is a device, in which the pressure of the sharpening material upon the razor edge may be controlled by the operator, thus overcoming the wear upon the sharpening material and allowing of a constant abutment of such material upon the razor edge.

Another object of my invention is a razor blade sharpening device free from revolving mechanism, thus greatly simplifying the device and avoiding the difficulties and dangers incident to the operation and use of such intricate mechanism.

Another object of my invention is a device of economic construction, which requires no expertness or particular care in its employment and which is not liable to become broken or inoperative through constant use.

The device of my invention possesses all of the above, and other, valuable attributes, as will be evident upon a consideration of my specification and its accompanying drawings, illustrating modified forms of my device and in which similar parts are designated by similar numerals.

Figure 1 is a perspective view of one form of the device of my invention.

Figure 2 is a section through the line 2—2 of Figure 1.

Figure 3 is a top view of Figure 1 with the upper member removed.

Figure 4 is a bottom view of the upper member of Figure 1.

Figure 5 is a perspective view of the blade carrier shown in Figures 2 and 3.

Figure 6 is a section through the line 6—6 of Figure 1.

Figure 7 is a vertical cross-section showing modified form of blade carrier.

Figure 8 is a top view of the device of Figure 7, with the top member removed.

Figure 9 is a top view showing a modified form of blade carrier.

Figure 10 is a top view showing a particular blade carried by the blade carrier.

Figure 11 is a top view showing a particular blade carried by the blade carrier.

Figure 12 is a top view showing a particular blade carried by the blade carrier.

The particular form of the device of my invention shown in Figures 1 to 6 and Figures 9, 11 and 12, inclusive, consists of a base having the bottom 20, the sides 21 and 22, the ends 23 and 24. The base has a longitudinal recess, or cut-out, in the upper portion forming the tops 25 and 26 of the base.

The base recess is formed by the two vertical sides 27, 28, the downwardly and inwardly inclined sides 29, 30, the downwardly and outwardly inclined sides 31, 32 and the horizontal bottom 33. Supported by, and attached to, the sides 29 and 30 are strips, or sheets, 34 and 35, of a sharpening or honing material, such as leather, rubber, glass or metal. Fixedly attached blocks 36 and 37 close the ends of the recess.

The upper member of the device consists of the top 38, the sides 39 and 40, and the ends 41 and 42. The upper member has a recess, or cut-out, similar to that of the base forming the two bottoms 43 and 44, the two upwardly and outwardly inclined sides 45 and 46 and the top 47. Supported by and attached to the two faces 43 and 44 are strips, or sheets, 48 and 49 of a sharpening or honing material such as leather, rubber, glass or metal. Fixedly attached blocks 50 and 51 close the ends of the recess.

The outer edges of the sharpening elements 34, 35, 48 and 49 are preferably bevelled as shown in Figure 2 in order to allow the pressure of these elements to bear upon the blade edge during the sharpening process.

A blade carrier consists of the bottom 52, the inclined sides 53 and 54, the ends 55 and 56 and the top 57. Carried by the blade carrier and extending above the top thereof are two pins 58 and 59.

The operation of the device is as follows:

The upper member is removed and a razor blade 60 is placed upon the blade carrier with the pins 58 and 59 extending through openings in the blade. The upper member is then replaced and moved longitudinally back and forth, the tops 25 and 26 acting as guides for such movement, during which the inner faces of the blocks 50 and 51 abut alternately upon the pins 58 and 59, thus moving the blade carrier back and forth and causing the blade edges to abut upon and move along the sharpening materials 34, 35, 48 and 49. It is evident that a downward pressure upon the top member will cause a close contact between the razor edges and the sharpening material. The longitudinal movement of the top member is limited by the abutment of the blade carrier upon the blocks 36 and 37 of the base.

Figures 7, 8, and 9, are similar to the one previously described except that the pins are differently arranged in order to operate with razor blades of different construction.

Figures 7 and 8 illustrate a blade carrier adapted for use with single edge blades of the "Gem" type, the pins 58 and 59 being positioned to one side of the longitudinal center line of the carrier.

Figure 9 illustrates a blade carrier adapted for use with single edge blades of the "Valet" or "Autoströp" type.

Figure 10 illustrates the adaptability of the described carrier to the new "Gillette" blade.

Figure 11 illustrates the adaptability of the described carrier to the "Probak" blade.

Figure 12 illustrates the adaptability of the described carrier to the "Duplex" blade.

It will thus be seen that my invention presents a simple and effective means for sharpening razor blades, economic of construction, free from parts liable to become disarranged or inoperative and the operation of which is of the simplest character.

I do not limit myself to the particular size, shape, number, arrangement or material of parts as shown and described as these are given simply as a means for clearly describing the device of my invention.

What I claim is:—

1. In a razor blade sharpener, in combination, a base member, sharpening material carried longitudinally by said base member and abuttable upon a razor blade carried by a blade carrier, a longitudinally movable blade carrier carried by said base member, means for limiting the longitudinal movement of said blade carrier along said base member, means for removably attaching a razor blade to said carrier, a top member longitudinally slidable over said base member and relatively to said blade carrier, sharpening material carried longitudinally by said top member and abuttable upon a blade carried by said blade carrier, and means for limiting the longitudinal movement of said top member relatively to said blade carrier whereby a movement of said top member will move said blade carrier and said means for limiting the longitudinal movement of said blade carrier will limit the longitudinal movement of said top member.

2. In a razor blade sharpener, in combination, a longitudinally shaped base member, sharpening material carried longitudinally by said base member and capable of abutment upon a razor blade carried by a blade carrier, a longitudinally movable blade carrier carried by said base member, means for limiting the longitudinal movement of said blade carrier along said base member, a plurality of extended pins carried by said blade carrier adapted to be inserted through openings in a razor blade positioned thereon, a top member longitudinally slidable over said base member, and relatively to said blade carrier, sharpening material carried longitudinally by said top member capable of abutment upon a razor blade carried by said blade carrier, and means including said pins for limiting the longitudinal movement of said top member relatively to said blade carrier whereby a movement of said top member will move said blade carrier and said means for limiting the longitudinal movement of said blade carrier will limit the longitudinal movement of said top member.

3. In a razor blade sharpener, in combination, a longitudinally shaped base member, two spaced

pieces of sharpening material fixedly attached longitudinally to said base and adapted to abut upon the edges of a razor blade carried by a blade carrier, a longitudinally movable blade carrier carried by said base member, means for limiting the longitudinal movement of said blade carrier along said base member, means for removably attaching a razor blade to said carrier, a top member longitudinally slidable over said base member, and relatively to said blade carrier two spaced pieces of sharpening material fixedly attached longitudinally to said top member and adapted to abut upon the edges of a razor blade carried by said blade carrier, and means for limiting the longitudinal movement of said top member relatively to said blade carrier whereby a movement of said top member will move said carrier and said means for limiting the longitudinal movement of said blade carrier will limit the longitudinal movement of said top member.

4. In a razor blade sharpener, in combination, a base member, sharpening material carried longitudinally by said base member and abuttable upon a razor blade carried by a blade carrier, a longitudinally movable blade carrier carried by said base member, means for limiting the longitudinal movement of said blade carrier along said base member, means for removably attaching a razor blade to said carrier, a top member longitudinally slidable over said base member, and relatively to said blade carrier sharpening material carried longitudinally by said top member and abuttable upon a blade carried by said blade carrier, means for limiting the longitudinal movement of said top member relatively to said blade carrier, whereby a movement of said top member will move said blade carrier, and means whereby an increased downward pressure upon the top member will increase the frictional contact between said sharpening materials and the edges of a blade carried by said blade carrier during the movement of said carrier, said means for limiting the longitudinal movement of said blade carrier also serving to limit the longitudinal movement of said top member.

5. In a razor blade sharpener, in combination, a longitudinally shaped base member, two spaced pieces of sharpening material fixedly attached longitudinally to said base and adapted to abut upon the edges of a razor blade carried by a blade carrier, a longitudinally movable blade carrier carried by said base member, means for limiting the longitudinal movement of said blade carrier along said base member, means for removably attaching a razor blade to said carrier, a top member longitudinally slidable over said base member and relatively to said blade carrier, two spaced pieces of sharpening material fixedly attached longitudinally to said top member and adapted to abut upon the edges of a razor blade carried by said blade carrier, means whereby a movement of said top member will move said carrier, and means whereby an increased downward pressure upon the top member will increase the frictional contact between said sharpening materials and the edges of a blade carried by said blade carrier during the movement of said carrier, said means for limiting the longitudinal movement of said blade carrier also serving to limit the longitudinal movement of said top member.

6. In a razor blade sharpener, in combination, a longitudinally shaped base member, sharpening material carried longitudinally by said base member, a separate top member longitudinally
